MACHINE FOR MAKING SANDPAPER AND
OTHER ABRASIVES

Walker Burns, St. Paul, Minn., assignor, by direct and mesne assignments, to Behr-Manning Corporation, Troy, N. Y., a corporation of Massachusetts

Application July 7, 1930, Serial No. 466,124

3 Claims. (Cl. 91—44)

My invention relates to making sandpaper and other abrasives, where it is desired to provide a sheet-like material with an abrasive surface on one side, such as sandpaper, emery cloth and other abrasives, and to provide a means for making the sandpaper or other abrasives of a more efficient nature and in a simple manner.

A feature of my invention resides in the means for making an abrasive material consisting in passing a sheet, which is coated with a binder or adhesive substance, such as glue or varnish, past an air operated means of blowing the fine particles of abrasive material against the sheet so that the particles will stand out and project from the sheet rather than lay down against the same and pile or compact in relation to each other. This permits the surplus particles of abrasive material to fall away from the surface to which the particles are to adhere to form the sandpaper or abrasive material, rather than pile against the particles attached to the sheet to make up the sandpaper, and thus the particles stand out like fine needles to form spaced abrasive particles projecting from the sheet supporting the same, and thereby providing a more efficient sandpaper or abrasive material than has been accomplished heretofore in so far as I know.

The features of primary importance will be fully and clearly pointed out with those here before set forth and such others as form an essential part of my invention.

In the drawings which I have illustrated to assist in carrying out my method:

Figure 1 is a diagrammatic side view of an apparatus adaptable for carrying out my method.

Figure 2 is a detail of a portion of the same.

Figure 3 is a detail of another portion of the same.

Figure 4 is a diagrammatic plan view of a portion of the apparatus.

Figure 5 is an end view of Figure 4.

Figure 6 is a detail of a portion of the apparatus.

Figure 7 is an enlarged cross section of a piece of sandpaper, or cloth made in accordance with my method.

The steps of operation of my machine for making sandpaper and other abrasives consist in carrying the fine particles of abrasive material, such as garnet, silicon carbide, flint, aluminum oxide or emery, or which may be of any nature ordinarily employed and used for the making of sandpaper, emery cloth and like materials, in an even spread out manner to a blower means over which the abrasive material passes while spread

out and which causes the abrasive material to be projected against the sheet carrying the abrasive. This may be accomplished by the apparatus A which is provided with a casing forming the enclosed compartment B in which the table 10 is positioned. The table 10 is adapted to support an endless belt 11 which travels over the driving pulley 12. The driving pulley 12 is adapted to be operated by a suitable electrical motor 13 which is positioned outside of the compartment B and which is connected by means of a pulley 14 to the motor 13.

The belt 11 travels in the direction of the arrow to extend over a blower head C which extends across between the sides of the table 10 and is of a sufficient width to correspond to the width of the belt 11 so that air may be passed from the blower head C through the belt 11.

The blower head C is formed with an adjustable air outlet slot 15 which may be adjusted to the desired width so that air may be blown through the slot 15 from the head C in a manner to force air through the belt 11. The belt 11 extends from the blower head C over the pulley 16 and down and over the adjustable pulley 17. The pulley 17 is carried by a diagonally extending brace 18 and may be adjustable upon the same to tighten the belt 11 if it is desired so that the proper tension may be maintained at all times upon the belt 11. Any other suitable belt adjusting means may be employed to keep the belt 11 at the desired tension.

Within the compartment B, I provide a hopper D for supporting a supply of abrasive material. The hopper D is formed with an adjustable gate 19 so that the abrasive material may be uniformly discharged out of the hopper, the same running over the forwardly projecting shelf 20 positioned below the gate 19.

In the lower portion of the casing or compartment B, a collecting hopper 22 is provided by the bottom wall of the casing for the surplus abrasive material and by means of the air nozzle 23 which is connected to a source of air by the pipe 24, the surplus abrasive material may be blown through the pipe 25 up to a hopper 26 which is positioned above the hopper D outside of the compartment B. The connection 25 may lead directly to the hopper D if it is so desired, so that the surplus abrasive material which is not used up in my method of making sandpaper and other abrasives in the operation of the apparatus A, will be carried directly back to the hopper D so that the apparatus A may operate automatically and continuous to carry out my method, and pro-

vide an abrasive material or sandpaper of the desired nature.

The sheet 28 which is adapted to form the backing or sheet of the sandpaper or other abrasive sheets to be made by my method, travels automatically into the compartment B, passing over the rollers 29 and 30, carried by the supporting bracket 31 on the table 10 and from the roller 30 the sheet passes back under the roller 32 and out of the compartment B. The roller 30 is adjustable on the bracket 31 by means of the slots 33 in the bracket bearing 34 for the roller 30, so that the same may be moved closer or farther away from the belt 11. The roller 32 may be adjustable in the same manner if it is desired.

The apparatus A operates to carry the fine abrasive particles spread out on the belt 11 to the blower head C. The belt 11 may be made of any suitable material so that air may pass through the same from the blower head C and yet of such a nature as to carry the abrasive material from the hopper D evenly spread out to the backing sheet 28. As the belt 11 passes over the blower head C, the air from the same passing out of the slot 15 blows the fine particles of abrasive material up against the backing sheet 28 which has been previously coated with an adhesive material, such as glue or varnish, or any other water-proof binder, before entering into the compartment B, and as the fine particles of abrasive material such as 36 are blown up against the sheet, they stick to the same by reason of having been shot up like darts against the binder which may be of any material, causing them to project out rather than lay down flat against the sheet as in sandpaper and abrasive sheets made by the old method. The surplus abrasive particles 36 will quickly and readily fall away from the backing sheet 28 and be gathered in the hopper 22 and automatically carried back to the hopper 26 or directly to the hopper D.

The sandpaper, emery cloth or similar material formed by my machine, such as is illustrated in Figure 7, has a better cutting quality, is more effective in its operation, and can be made economically. When the particles are blown to the backing sheet, either for plain or water-proof sandpaper or fabric, in the manner set forth in my method, they do not collect one against the other but the adhesive surface of the backing sheet will just take up the right number of particles to make the most effective and efficient abrading surface for sandpaper or other similar sheet abrading materials.

In accordance with the patent statutes, I have endeavored to describe my apparatus, and while I believe the apparatus that I have set forth is the best embodiment of my invention, I desire to have it understood that the same may be varied within the scope of the following claims without departing from the spirit, purpose and intent of my invention.

I claim:

1. The new article of manufacture in apparatus for making sandpaper or emery cloth comprising, a hopper for abrasive particles, an opening from

said hopper to feed a thin layer of the abrasive particles out of said hopper, an endless belt adapted to pick up the thin layer of abrasive particles, a blower beneath said endless belt adapted to blow the abrasive particles off of said belt, means for adjustably carrying the flexible backing sheet of the sandpaper or the like with a coat of adhesive over the surface thereof exposed at a point adjacent said blower and endless carrier, whereby the abrasive particles carried by said belt are blown by said blower into the surface of the adhesive on the flexible sheet to automatically coat the surface of the sheet with the abrasive particles standing out individually one from the other.

2. The new article of manufacture in apparatus for making sandpaper or emery cloth comprising, a hopper for abrasive particles, an opening from said hopper to feed a thin layer of the abrasive particles out of said hopper, an endless belt adapted to pick up the thin layer of abrasive particles, a blower beneath said endless belt adapted to blow the abrasive particles off of said belt, means for adjustably carrying the flexible backing sheet of the sandpaper or the like with a coat of adhesive over the surface thereof exposed at a point adjacent said blower and endless carrier, whereby the abrasive particles carried by said belt are blown by said blower into the surface of the adhesive on the flexible sheet to automatically coat the surface of the sheet with the abrasive particles standing out individually one from the other, a hopper for receiving surplus abrasive particles from said endless belt, and means for pneumatically conveying said surplus abrasive particles from said last-mentioned hopper to said first-mentioned hopper.

3. The new article of manufacture in apparatus for making sandpaper or emery cloth comprising, a hopper for abrasive particles, an opening from said hopper to feed a thin layer of the abrasive particles out of said hopper, an endless belt adapted to pick up the thin layer of abrasive particles, a blower beneath said endless belt adapted to blow the abrasive particles off of said belt, means for adjustably carrying the flexible backing sheet of the sandpaper or the like with a coat of adhesive over the surface thereof exposed at a point adjacent said blower and endless carrier, whereby the abrasive particles carried by said belt are blown by said blower into the surface of the adhesive on the flexible sheet to automatically coat the surface of the sheet with the abrasive particles standing out individually one from the other, a hopper for receiving surplus abrasive particles from said endless belt, means for pneumatically conveying said surplus abrasive particles from said last-mentioned hopper to said first-mentioned hopper, and a wall structure enclosing said endless belt, said blower, and carrying means for the flexible backing sheet, a portion of said wall structure forming said hopper for the surplus abrasive particles received from said endless belt.

WALKER BURNS. 65
